UNITED STATES PATENT OFFICE.

HARRY W. JORDAN, OF SYRACUSE, NEW YORK.

WATER-HEATING ELEMENT.

Application filed June 2, 1924. Serial No. 717,290.

To all whom it may concern:

Be it known that I, HARRY W. JORDAN, a citizen of the United States, residing at Syracuse, in the county of Onondaga and 5 State of New York, have invented certain new and useful Improvements in Water-Heating Elements, of which the following is a specification.

This invention relates to an improved 10 water heating element, designed for use in connection with hot-air and other heaters, by means of which water for storage purposes and hot-water radiation, as well as, for humidifying air of dwellings and the 15 like, may be economically and effectively heated.

The primary object of the invention is to provide a water heating element, of novel and simple design, adapted to be applied to 20 the fire-pot or other heated portion of a furnace and the like, to take the place of the simple coil (so-called) heretofore inserted into the hot-air and other heaters, wherein the water from the service mains is carried 25 directly into the combustion chambers by a single pipe, which is usually bent upon itself and provides a continuous conduit of substantially the same caliber throughout, by which the inflow of the cold water and 30 the outflow of the hot-water is effected.

The present water heating element consists of a single hollow body or manifold, which constitutes the heating element proper, into which is inserted a relatively 35 small water-supply pipe, that carries the cold water to the remote end of the element where the water is discharged into the relatively spacious interior of the element, to be heated and circulated therein and around 40 the feed pipe by gravity, and from which the hot water and steam are discharged from the same end at which the water supply pipe enters, and at a level and under such conditions as to facilitate the exit flow and to obviate 45 noise and hammering. A further object is to provide an elongated leg, by which the normal depth of the element is increased 50 downwardly, the said leg being arranged to contain a relatively thin body of water, and 55 may be projected still farther into the hot zone of the fire, for quickening and for greatly increasing the efficiency of the heating element. A further object is to still further increase the heat induction area of the element by providing at the top and bottom thereof relatively thin solid elongated fins,

by which the heating action of the element is intensified. These fins may be employed in connection with the hollow leg, or the fins may be used alone, singly or in multiple, 60 when the degree of efficiency calls for such construction and use.

A particular object of the invention is to provide a novel, simple and effective system 65 for heating water for storage and for humidifying air, which embraces my improved heating element; the said element being disposed entirely within the smoke pipe adjacent a furnace or other heater, within the hottest zone of the waste products of combustion, which usually escape via the chimney. This utilization of the heat of the waste products of a furnace, which ranges 70 from 200° to 400° F., during the heating seasons, enables me to operate my system effectively and continuously for long intervals, 75 without any cost, except the initial expense of installing the heating element and related parts.

The various features and parts of the invention will be understood from the detailed description which follows, and by reference 80 to the accompanying drawings, in which—

Figure 1 is a broken plan view of a hot-air furnace, and a section of the smoke pipe, 85 to which my improved water heater is applied. Fig. 2 is a vertical cross-section, taken on line 2—2 of Fig. 1. Fig. 3 is a rear-side elevation of the smoke pipe. Fig. 4 is an enlarged vertical longitudinal section 90 through one form of the heating element. Fig. 5 is an elevational view of a slightly modified heating element. Figs. 6 and 7 are similar broken elevational views of the furnace, showing different ways of disposing 95 the heating elements relatively to the fire-pot; also showing slight variations in the application and arrangement of the flow and return piping. Fig. 8 is a view; showing the heating element without the leg or fins. 100 Fig. 9 is a view; showing the heating element with top and bottom fins. Fig. 10 is a vertical cross-section, taken on line 10—10 of Fig. 9. Fig. 11 is a rear-end view of the element shown in Fig. 9. Fig. 12 is an elevational view; showing the smoke pipe containing the heating element disposed at an incline for consistently heating the element. Fig. 13 is a view of the sectional water supply pipe, which is shown inserted into the 105 several heating elements. And Fig. 14 is a view; showing the butterfly damper disposed 110

in the smoke pipe beyond the heating element.

In the drawings, 2 represents conventionally a heater, of the hot-air or like type, 5 in common use. 3 is the smoke outlet pipe, in which is shown the usual disc or butterfly damper 3'. In order to show a convenient and practical application of my water heating element, I provide a somewhat special 10 design of smoke conduit, as 4, which is preferably oval in cross-section, as best seen in Fig. 2, into which the short pipe 3 discharges the gaseous waste products of the furnace, preferably near the bottom of said 15 conduit. The conduit 4 is preferably three or four feet in length, and is normally open at its opposite ends, the said ends being closed during the operation of the furnace, by similar caps 4' and 4", which may be 20 readily removed for installing the heating element 5, as well as for cleaning and inspecting the conduit and element. Near its remote end the usual vertical smoke pipe 6 taps the top side of the conduit, and to the 25 pipe 6 is applied the usual check damper 6', by which the draft of the furnace is controlled, in a well-known manner, and for this purpose the pipe 6 is tapped by a short horizontal pipe 6".

30 The water heating element is preferably disposed in or slightly above the longitudinal axis of the conduit 4, the head end of the element preferably being positioned directly opposite the smoke outlet 3, while 35 its remote end is preferably disposed directly beneath the opening leading to the pipe 6, as shown in Figs. 1 and 3. By this arrangement, the hot products from the furnace are compelled to travel the full 40 length of the element 5 before passing into the pipe 6. The heating element is preferably supported near its remote end by a stirrup 7, which is suspended from the top wall of the conduit, by means of a bolt 7' that passes upwardly through a boss 4", and may be adjusted and held in place 45 by a nut 7". The head end of the heating element is supported in part by a nipple or pipe 8, which is inserted downwardly 50 through an opening in a boss 4" formed at the top of the conduit, the said pipe being screwed into a relatively large opening 5', through which the products of the element 55 are discharged. A collar 8' carried by the pipe 8, and a set-screw 8" afford convenient and suitable means for adjusting and holding the parts in the proper position, as shown. The pipe 8 performs the usual functions of a flow-pipe, by which the products of the element 5 may be carried to a storage tank, or to a hot-water radiating system (not shown).

60 My heating element in its preferred form shown in Fig. 4, consists of a cast-iron body or manifold 5, which is preferably hollow

throughout, and the body proper preferably tapers upwardly from the remote end towards the head, the smaller end having an opening 5", principally for convenience in casting, but also serves for inspecting and 70 cleaning the element, the said opening being sealed by a plug 5". The outlet 5' for the hot-water and steam, is preferably disposed at the top of the head end, where the body is hollowed upwardly, as at 5", for providing 75 space for the accommodation of steam; the said enlargement together with the size and disposition of the outlet 5' tending to prevent noise and hammering, when the element is heated above normal. The water to be heated by the element is supplied by a relatively small caliber pipe 9, which may receive the water from an ordinary service main, or other source. The pipe 9 is preferably supported by a bushing 9', which 80 is threaded into an opening 5" in the head end, and said pipe thence extends inwardly to within an inch or two of the remote end of the manifold 5, at which point the said pipe discharges the water freely into the relatively spacious interior of the manifold. 85 After the water leaves the pipe 9 it is heated and gravitates back through the manifold towards the outlet 5'. This gravitation of the hot-water and steam is facilitated by the gradual upward slope of the top wall of the element, and in case considerable steam pressure is generated in the element, the enlargement 5" affords ready relief and besides eliminates noise and knocking, common to many of the older water heating systems. The efficiency of my heating element may be materially increased by forming the bottom of the element 5 with a hollow tapering depending portion, as 5", which extends from a point near the discharge end of the pipe 9 forwardly towards the head end of the body, and is arranged to contain a relatively thin body of water, which is readily and quickly heated to a 100 high degree. The leg 5" may also be formed with a thin solid downward extending fin or rib 5'. 5" represents a similar but preferably longer solid fin, which may be disposed centrally along the top side of the body 5, for absorbing more or less of the heat that accumulates in the top portion of the conduit 4. By providing the leg 5" and the fins 5"-5", greatly increases the heat induction, and correspondingly raises the 105 efficiency of the heating element, as compared with the plainer construction and arrangement of the element, as shown in Fig. 8. The water supply pipe 9 may be in two sections, as 9 and 9" (see Fig. 13). 110 When the two sections are provided, the pipe 9 together with the bushing 9', may be applied to the element 5 before it is inserted in the conduit 4, and the section 9" 115 may afterwards be inserted through an 110

115

120

125

130

135

opening in the cap 4' and screwed into the bushing. The dotted lines in Fig. 3 show how the cap 4' may be detached and moved along the pipe 9', for facilitating cleaning 5 out and inspecting the conduit and the element. The heating element 5 is preferably so disposed in the conduit that any suitable swab or cleaning tool may be operated lengthwise in the conduit, when the caps 4' 10 and 4^a are removed, without disturbing the water heating parts.

In Fig. 6 the heating element is shown in the doorway of the ordinary hot-air furnace; the tapering body portion preferably 15 extending horizontally across the fire-pot 2', while the enlarged head-end of the element projects outwardly beyond the jacket of the furnace, where the flow and return fittings are applied directly to the head. In this 20 view, the heating element is equipped with the hollow leg 5^e, but the top and bottom fins are omitted.

In Fig. 7, the heating element is wholly 25 positioned inside the combustion chamber of the furnace, the head-end resting on the doorway ledge 2^a, in a manner to incline the body 5 downwardly into the fire. The head-end of this element is provided with a single relatively large threaded opening into 30 which is screwed a nipple 10; the latter projecting through the jacket and connecting with the usual flow-pipe 10'. In this view, the water supply pipe 9 is shown inserted through the nipple and thence into the element, the latter being provided with the hollow leg 5^e and also with the bottom fin 5^f, as described.

In Fig. 5, the leg 5^e and the fins 5^f-5^x 40 are preferably extended substantially the full length of the tapering portion of the element, and a single outlet and inlet opening similar to that shown in Fig. 7 is provided in the head-end. Fig. 8 illustrates a plain heating element adapted for relatively 45 low efficiency. And Fig. 9 shows a similar element, which is provided with top and bottom fins, but without the leg 5^e.

Fig. 12 illustrates a slightly modified arrangement of the conduit 4^c, which consists 50 of inclining the conduit, for forcing the hot waste products of the furnace downwardly as they progress towards the outlet 6, for more effectually and consistently heating the remote end of the element.

55 In Fig. 14, I have shown the preferred location and arrangement of the damper 3'. By placing this damper in the pipe 6, instead of in the pipe 3, the conduit 4 may be maintained at a considerably higher temperature, which correspondingly adds more heat to and increases the efficiency of the water heating element.

60 The several modifications of the heating element herein shown and described, are all 65 operated on practically the same principle.

The variations merely affecting the degree of the heating; the minimum degree being attained by the element shown in Fig. 8; while the maximum degree may be attained by the use of the element shown in Figs. 4 70 and 5.

Having thus described my invention, what I claim, is—

1. A water heating element comprising an elongated hollow body adapted to be disposed in a heated zone of a furnace, said body having a depending hollow tapering leg adapted to contain a thin body of water, the top wall of said body opposite said leg inclining upwardly towards the head end, said head end having a relatively large opening for the exit of the hot water, and a water supply pipe of relatively small capacity disposed longitudinally in the body adapted to conduct water to be heated substantially the full length of the hollow interior of the body and to discharge the water beyond the remote end of the said leg. 75

2. A water heating element for supplying hot-water to storage tanks and the like, comprising an elongated hollow body having a discharge opening at one end, the top of said body tapering downwardly from said opening towards its remote end, radial fins 90 projecting above and below the body for increasing the heat induction when the body is exposed to a fire, and a pipe entering the body near said opening and extending inwardly longitudinally adapted to deliver water to be heated near the remote end of 95 the body. 100

3. A water heater comprising an elongated hollow body whose top tapers substantially from end to end, the larger end thereof having an opening for the discharge of the water, the smaller end being closed, the bottom of said body being formed with a depending tapering hollow leg, a thin fin depending from said leg, a similar fin rising from the top of the body, and a water supply pipe of smaller capacity than said discharge opening entering the larger end of the body adapted to discharge water to be heated close to the smaller end of the body. 105

4. The combination with the smoke pipe 115 of a furnace, of a water heating element disposed longitudinally in said pipe in the path of the hot products of combustion received by said pipe from the furnace, said element comprising an elongated hollow tapering body adapted to be charged with water to be heated, a pipe of relatively small caliber entering the end of the element nearest the furnace, and being arranged to discharge the water near the remote end of the element, the water while being heated adapted to entirely surround said water pipe 120 and to circulate back towards the end of the element at which said water pipe enters, and a relatively large caliber flow pipe tap- 125 130

ping the end of the element nearest the furnace for conducting the hot-water and steam from said body.

5. A water heating element adapted to be heated by the waste products of a furnace, comprising an elongated hollow tapering body adapted to be suspended in the furnace smoke pipe, said body having a relatively large opening in its head end for the exit 10 of the water, and having its remote end closed, a feed-water pipe of relatively small caliber inserted through the head-end and extending towards the remote end adapted to discharge cold water in the zone of the 15 smallest diameter of the element, the water while being heated completely submerging said pipe raising the temperature of the water before it is discharged by the pipe, and means for heating portions of the water 20 below the normal bottom level of said body.

6. The combination with a furnace and a smoke pipe for carrying off the waste products of combustion having a butterfly damper for controlling the draft of the furnace, of a water heating element disposed 25 in said smoke pipe between the furnace and said damper, means for adjustably supporting the element in said pipe, said element comprising an elongated hollow tapering 30 body, the larger end of said body being disposed nearest the furnace and having a

relatively large opening for the exit of the hot water, and a water supply pipe piercing the larger end of the body and extending longitudinally therein adapted to discharge 35 cold water close to the smaller end of the body.

7. Means for heating water for storage purposes, comprising a hollow body adapted to be heated by the waste products of combustion of a furnace, said body tapering in the direction of the flow of said products, a pipe for supplying cool water to said body, said pipe being inserted through the larger 40 end of said body and extending inwardly towards and adapted to discharge the water near the smaller end of said body, said body having a hot-water outlet opening adjacent its larger end and having an enlargement below said opening for obviating 45 noise and hammering during the operation of the heater, said water supply pipe adapted to be surrounded and warmed by the water as the latter becomes heated and circulates back towards said discharge opening, and a series of integral radial projections 50 for increasing the normal heat induction area of the body.

In testimony whereof I affix my signature.

HARRY W. JORDAN
